JAR LIFTER

Frederick Hildenbrand, Stockton, Calif.

Application April 9, 1937, Serial No. 136,027

2 Claims. (Cl. 294—34)

This invention relates to a jar lifter and it consists in the constructions, arrangements and combinations herein described and claimed.

It is an object of the invention to provide a jar or can lifter which may be employed upon containers of various diameters and in which the jar-gripping jaws readily adjust themselves to the contour of the container.

It is also an object of the invention to provide a structure which is readily manipulated to firmly grasp a jar or similar container and which may be manufactured at a low cost.

Additional objects, advantages and features of invention will be apparent from the following description and accompanying drawing, wherein

Figure 1 is a side elevation of a jar having my device applied.

Figure 2 is a top plan view thereof, a portion of the jar being shown in elevation.

20 There is illustrated a handle portion 10, in which a shank 11 is rigidly fixed, one end of the shank extending beyond the handle and has mounted thereon an L-shaped bracket 12. The bracket comprises a long leg 13 extending in a plane coincident with the shank 11 and a short leg 14 extended at right angles to the shank 11. The leg 14 includes an inturned lip 15, the latter lying in a plane parallel to the leg 13.

30 A bracket 16 shaped somewhat similar to the bracket 12 is slidably mounted thereon as will now be described. The leg 17 of the bracket 16 is positioned immediately above and slidably contacts the leg 13, the leg 17 being of a length 35 stopping short of the handle 10 and has a downwardly turned end 18. The end portion 18 is apertured and receives the shank 11 therethrough. A helical spring 18a is positioned on the shank 11 one end abutting the leg 14 and the other end 40 resting against the end portion 18.

The other end of the bracket 16 has a leg 19 extended downwardly and lies in a plane parallel with the leg 14, and adjacent the extremity of the leg 19 an inturned lip 20 is formed lying in the 45 same plane as the lip 15.

Upon each of the lips 15 and 20 a gripping jaw 21 is pivotally mounted as at 22. The jaws 21 are identical in construction, and as may be seen in Figure 2, are crescent-shaped, the curvature 23 being such as to readily fit the contour of a jar or can.

A slot 24 is formed in the leg 17, extending longitudinally thereof, for a suitable distance, and a rivet 25 mounted in the leg 13 is positioned in the slot.

An upstanding thumb lug 26 is formed upon the leg 17 positioned adjacent the handle 10.

The operation.

The operation will be readily understood from the following description. Housewives often find it necessary to remove jars and cans from boiling water or the oven of a stove, especially during canning time, and with my device, it will only be necessary to grasp the handle 10, and exert forward pressure upon the lug 26, compressing the spring 18a. Obviously, the bracket 16 is moved forwardly carrying the leg 19 with it, thereby causing separation of the jaws 21 and permitting ready placement of a jar or can therebetween. It is now only necessary to release pressure on the lug, the expansion of the spring 18a returning the bracket 16 to its normal position with the jaws 21 firmly engaging the can or jar.

While I have shown and described a preferred form of the device, this is by way of illustration only, and I consider as my own all such modifications in structure as fairly fall within the scope of the appended claims.

I claim:

1. A jar or can lifter comprising a handle having a shank, a bracket fixed to the shank but spaced from the end of the handle, the bracket having a leg disposed at right angles to the shank, the leg having a right angularly disposed gripping jaw, a bracket slidably mounted upon the first named bracket, one end of the bracket having a leg extended to lie in a plane parallel to the leg of the first named bracket, a right angularly disposed gripping jaw on the last named leg, said last named bracket having a downturned portion apertured to receive the shank therethrough, a compressible means between the downturned portion of the bracket and the first named bracket, an upstanding lug on the last named bracket in proximity to the handle, said second named bracket having a longitudinally extended slot, and rivet on the first named bracket and disposed in the slot.

2. A jar or can lifter comprising a handle having a shank fixed therein, a bracket secured to the end of the shank, said bracket having a leg extended in a plane coincident with the shank, a right angularly disposed leg on the bracket, a lip on the last named leg and extended at right angles thereto, a crescent shaped jaw pivotally mounted on the lip, a rivet carried by the first named leg, a second bracket, said second named bracket having a leg in contacting relation with the first named leg of the first bracket and hav-

ing a slot for accommodation of the rivet, said leg further having a downturned apertured portion receiving the shank therethrough, a helical spring on the shank interposed between the down-turned portion and the right angularly disposed leg of the first named bracket, said second named bracket having a right angularly disposed

leg, a lip on the leg disposed at right angles thereto, a crescent shaped jaw pivoted on the lip and in opposing relation to the first named jaw, and an upstanding lug on the second named bracket in proximity to the handle. 5

FREDERICK HILDENBRAND.
